BAG CLOSING AND SEALING MACHINE

Helmer Anderson, Minneapolis, Minn., assignor
to General Mills, Inc., Minneapolis, Minn., a
corporation of Delaware

Application August 16, 1934, Serial No. 740,063

13 Claims. (Cl. 93—6)

This invention relates to new and useful improvements in bag closing and sealing machines, and more particularly to machines of the type shown in my Patent No. 1,984,049, issued December 11, 1934.

An object of the present invention is to provide means for completing the final step of closing and sealing the open bag top, whereby the bag top walls will be folded smoothly and firmly into engagement with the bag body to thereby provide a very neat and attractive appearing bag.

A further object of the invention is to provide a mechanism operable in connection with a bag closing and sealing machine to complete the final operation of sealing the bag top, which has a member mounted for movement transversely to the line of travel of the bag, adapted to engage the partially folded bag top with a wiping action, whereby the bag top is smoothly folded into contact with the bag body.

Other objects of the invention reside in the novel construction of the means for completing the final operation of closing the bag top, whereby said mechanism may readily be adapted for handling bags of different sizes; in the provision of a shoe member for engaging the partially folded bag top walls with a wiping action, to thereby fold them smoothly into engagement with the bag body, whereby the walls of the bag top cannot buckle or wrinkle during the final folding operation thereof; in the means provided in connection with said shoe member for preventing the partially folded bag top walls from unfolding, prior to being engaged by the shoe, and whereby said means acts as a straight edge against and over which the partially folded bag top walls are folded, said member operating in timed relation to the travel of said shoe member, and in such a manner that it moves out of engagement with the bag top, when the shoe member has partially folded the latter into engagement with the bag body, to thereby permit the bag top to be firmly folded into direct engagement with the bag body.

Other objects of the invention will appear from the following description and accompanying drawings and will be pointed out in the annexed claims.

In the accompanying drawings there has been disclosed a structure designed to carry out the various objects of the invention, but it is to be understood that the invention is not confined to the exact features shown as various changes

may be made within the scope of the claims which follow.

In the drawings:

Figure 1 is a plan view of a portion of a bag closing and sealing machine showing the invention embodied in the construction thereof; 5

Figure 2 is a side elevational view of Figure 1, showing in part the means for driving the gumming mechanism;

Figure 3 is a cross-sectional view on the line 10 3—3 of Figure 2, showing the means for completing the final folding of the bag top;

Figure 4 is a cross-sectional view on the line 15 4—4 of Figure 2, showing the position of the parts when the bag top has been folded into engagement with the bag body;

Figure 5 is an enlarged detail sectional view showing a bag positioned beneath the folding means; and

Figure 6 is a detail sectional view on the line 20 6—6 of Figure 3, with some of the parts omitted.

The novel mechanism herein disclosed is shown used in connection with a machine of the general type shown in my patent, hereinbefore mentioned, and as that portion of the bag closing and sealing machine herein illustrated is substantially the same as that shown and described in the above mentioned pending application, it will be unnecessary to herein describe the same in detail. 25

Briefly, the bag closing and sealing machine comprises a bed plate 2, which constitutes the bottom of a conveyer having side walls 3 and 4, the former extending substantially the full length of the machine, as best shown in Figure 1. A conveyer chain 5 is shown supported at one end by a suitable sprocket 7, and the opposite end thereof is supported upon a similar sprocket, not shown in the drawings. The conveyer chain 5 is driven by a suitable mechanism, not shown, and which operatively connects it with the main operating shaft 8 of the machine, which has an operative connection with the drive shaft 9. The conveyer chain is provided with a plurality of flights 11 which engage the bags or containers delivered to the conveyer, and thereby feed them lengthwise through the machine between the conveyer walls 3 and 4. The wall 4 of the conveyer is provided at 10 with a suitable gap, through which the flights 11 of the chain 5 pass, when they leave the conveyer on their return travel. 30

It is to be understood that before the bags are delivered to the novel mechanism forming the subject matter of the present application, the open top walls thereof have been partially folded 55

into closing relation by making one or more transverse folds therein. Mechanisms suitable for thus initially folding the walls of the open bag tops are shown and described in my patent, No. 5 1,772,824, and form no part of the present invention.

In the drawings I have shown a gumming mechanism for applying a coating of gum to certain surfaces of the bag top or body, or to both, for securing the folded bag top directly to the bag body in sealing relation, but it is to be understood that the invention may be used in connection with other types of bag closing and sealing machines in which the folded bag tops 10 are not secured directly to the bag bodies by gumming surfaces thereof, as above stated, but wherein the bag tops are secured in sealing relation by gummed tape or sealing strips.

The gumming mechanism herein shown briefly 20 comprises a pair of horizontally disposed pressure rollers, not shown, which engage the partially folded bag top and press the walls thereof into flatwise relation while supported in substantially a vertical position. The bag top then passes into 25 engagement with a gumming wheel 45, which applies a coating of gum to the partially folded bag top at the point indicated at 48 in Figure 3, after which the bag top passes between suitable guide members 49 and 50, which, it will be noted by 30 reference to Figure 6, are spaced apart to provide a gap 51 adapted to receive the upstanding, partially folded bag top. The gumming mechanism also comprises a suitable receptacle 41 adapted to contain a suitable adhesive or gum which is 35 conveyed therefrom and applied to the bag top by the gumming wheel 45. The latter is shown having a suitable drive, generally indicated by the numeral 52. This drive is shown in detail in my pending application, above mentioned, and 40 it is therefore thought unnecessary to herein describe the same in detail.

The novel bag top folding mechanism herein disclosed is shown comprising a folding member or shoe 60, secured to the lower end of an arm, 45 generally indicated by the numeral 61. This arm comprises spaced members 62 having their lower ends shown integrally connected to a plate portion 63, to which the shoe 60 is directly secured. The upper end of the arm 61 is pivotally supported 50 upon a pivot pin 64, supported in suitable brackets 65, shown secured to an upstanding frame portion 66, which, in turn, is secured to the bed plate 2 of the machine.

The shoe 60 is preferably shaped, as shown in 55 Figures 3 and 4, and has its leading edge portion 67 curved upwardly, whereby it may engage the partially folded bag top, indicated at 68, and fold it downwardly into engagement with the bag body, as shown in Figure 4, by a sliding action.

The shoe 60 is operated by a connecting rod 69, having one end pivotally connected to the lower portion of the arm 61 by a pivot pin 71, and having its opposite end pivotally connected to an operating arm 72, pivoted at 73, and having its lower end shown provided with a roller 74 adapted 65 to travel in a groove 75 in a cam 76. The cam 76 is shown secured to the operating shaft 8, and is therefore adapted for direct rotation therewith. By thus connecting the arm 61 to the operating arm 72, when the cam 76 is rotated, an oscillating movement is imparted to the arm 61, whereby the shoe 60 will travel in a path cross-wise to the travel of the bags. The movement of the shoe is so timed, that each time a bag is delivered to a position directly beneath the shoe 60,

as shown in Figure 3, the cam will be operated to actuate said shoe. It is to be understood that during the operation of the shoe, the bag remains stationary in the position shown in Figures 3 and 4, as a result of the conveyer chain 5 being operated intermittently. 5

In order that the partially folded bag top 68 may be accurately and squarely folded into engagement with the bag body, a member, generally indicated by the numeral 77, is adapted to cooperate with the shoe 60 to hold the partially folded bag top 68 in longitudinal alinement with the travel of the bag, and against and over which the bag top 68 is folded by the shoe 60, when the latter is operated. 10

The member 77 is shown having a straight edge 78 slightly curved at one end, as indicated at 79, and which normally is spaced from the adjacent portion of the shoe 60 to provide a gap therebetween adapted to receive the partially folded bag top, as indicated by the dotted lines 81 in Figure 6. One corner of the shoe 60 is also rounded or curved, as indicated at 82, whereby the bag top may more readily enter the gap provided between the straight edge and the shoe 60. The member 77 is shown secured to a plate portion 83 having a pair of arms 84 and 85 shown integrally secured thereto and having their upper ends pivotally connected thereto, the upper ends of which are pivotally supported upon the pivot pin 64, as clearly illustrated in Figures 3 and 5. The arm 84 extends upwardly beyond the pivot pin 64 and has one end of a spring 86 shown connected thereto, the opposite end of which is secured to a small bracket 87 secured to the upstanding frame portion 66. An adjustable stop 88 is positioned to be engaged by the upper end of the arm 84 to thereby limit the forward movement of the straight edge 78. The stop 88 is secured in adjusted position by an 40 adjusting screw 89. 20

To actuate the straight edge 78, a screw 91 is shown received in threaded engagement with the plate portion 83, and is adapted to be engaged by an abutment member 92 provided upon one of the spaced members 62 of the arm 61, as will be clearly understood by reference to Figures 3, 4, and 6. Thus, the straight edge is actuated by movement of the arm 61 of the shoe 60, so that when the latter is moved forwardly, the abutment 92 will engage the terminal of the screw 91 and thus impart a swinging movement to the straight edge 78, as shown in Figure 4. When the shoe 60 returns to its normal position, shown in Figure 3, the abutment 92 of the arm 61 will move out of engagement with the screw 91, as soon as the upper end of the arm 84 engages the stop 88, thereby enlarging the gap between the straight edge and the adjacent side of the shoe 60, so that the bag top may readily be received between 50 said parts, as indicated in Figure 6. 55

The adjusting screw 89 provides means whereby the position of the straight edge may be adjusted transversely of the conveyer so as to accurately position it with respect to the shoe member 60 and the partially folded bag top 68. The straight edge 78 is provided with elongated slots 93 for receiving the screws 94 which secure the straight edge to the plate portion 83, and whereby the shoe may be conveniently adjusted 60 in a vertical direction to properly align it with respect to the bag top. 70

The shoe 60 may be adjusted transversely with respect to the conveyer by varying the length of the connecting rod 69. In Figures 1, 3 and 4 of 75

the drawings, I have shown one end of the connecting rod provided with means whereby the length thereof may readily be varied in a manner well-known in devices of this kind. Means is also provided whereby the shoe 60 and member 71 5 may be vertically adjusted with respect to the bag top and, as best shown in Figures 2 and 4, consists of adjustably mounting the brackets 65 upon the frame member 66 by suitable screws 95 traversing slots 96 provided in the upper portion 97 10 of the frame 66.

The guide 50 is also adjustably mounted whereby it may be positioned to suit the size of the bag. To thus adjust the guide member 50, it is 15 shown adjustably mounted upon a bracket 98 by suitable screws 99 received in elongated apertures 101 provided in the guide member 50. The screws 99 and slots 101 permit the forward edge 70 of the guide member to be moved with respect 20 to the member 49 to thereby properly adjust it with respect to the bag top 51, indicated in dotted lines in Figure 6. The guide member 50 may also be angularly adjusted with respect to the horizontal, as shown in Figure 3, by manipulation of the screws 103 received in the slots 102, 25 and which secure the bracket 98 to the frame member 66. The guide member 49, in like manner, is relatively movable in a direction crosswise of the conveyer by suitable means such as indicated 30 at 80 in Figure 6. Thus the gap 51 may be longitudinally aligned with the opening provided between the adjacent portions or edges of the members 60 and 71, and the gap 51 may also be varied in width to suit the size of the bag top.

35 Thus, it will be seen that the various parts of the novel mechanism herein disclosed are relatively adjustable whereby the mechanism may be quickly adjusted to adapt it for bags of different sizes.

40 An important feature of the structure resides in the particular construction and operation of the shoe member 60, whereby the latter has a wiping action upon the bag top when folding it into closing relation, as shown in Figure 4. This 45 assures that the bag top will be squarely and smoothly folded into engagement with the bag body in such a manner that the material or paper constituting the bag top walls, cannot buckle or wrinkle, which frequently occurs when using 50 bag closing and sealing machines of ordinary construction.

The provision of the straight edge 78 is also important in that it positively prevents the partially folded bag top from unfolding, when delivered to a position in front of the shoe 60. It 55 holds the partially folded bag top in the position shown in Figure 3 until the shoe 60 has commenced its forward movement and partially folded the bag top over against the bag body, 60 whereupon the abutment 92 engages the screw 91 and thereby moves the straight edge out of the way so that the partially folded bag top 68 may be folded into contact with the bag body, as clearly illustrated in Figure 4.

65 The shoe 60 is so shaped and positioned with respect to the bag body that when it is actuated by the connecting rod 69, it will exert a downward pressure upon the folded bag top, as will be understood by reference to Figure 4. The cam 70 groove 75 in the cam 76 is shaped so as to cause the shoe 60 to be temporarily retained in the position shown in Figure 4, until the bag is moved from beneath the shoe by one of the flights 11 of the conveyer chain and under a pressure member 104, secured in position over the line 75

of travel of the bags, and which is adapted to exert a slight downward pressure upon the tops of the bags to thereby hold the sealed bag top in such position until the gum has had time to set. The pressure member 104 is shown supported upon suitable members 105, shown in Figure 6, and is vertically adjustable to adapt it for bags of different heights.

By the employment of this novel folding mechanism in connection with a bag closing and sealing machine, each bag discharged from the machine will have its top neatly folded into sealing engagement with the bag body in such a manner that the top of the bag is smooth and neatly shaped, and is free from wrinkles and other unsightly marks, often resulting when folding the bag tops with ordinary folding mechanisms. The folding mechanism is comparatively simple and inexpensive and is universally adjustable so that it may be adapted for handling bags of different sizes and shapes. It operates in timed relation to the travel of the bags and is so timed that it operates only during the interval when a bag is at rest between the shoe member 60 and the member 71.

In the drawings, I have shown the folding mechanism as used in connection with machines such as disclosed in my pending application, hereinbefore mentioned, but it is to be understood that it may be used in connection with various other types of bag closing and sealing machines where applicable without departing from the scope of the invention.

I claim as my invention:

1. In an apparatus for closing and sealing filled containers whose open tops have previously been partially closed, means for advancing the containers, and a mechanism positioned to receive the partially folded container tops comprising a member mounted for swinging movement crosswise to the line of travel of the containers and from a pivot disposed at an elevation above said line of travel, whereby said member will engage each partially folded container top with a wiping action, and fold and press it into contact with a portion of the container body. 40

2. In an apparatus for closing and sealing filled containers whose open tops have previously been partially closed, means for advancing the containers, a mechanism positioned to receive the partially folded container tops comprising a member mounted for swinging movement crosswise to the line of travel of the containers from a pivot disposed above the containers and substantially in the medial plane thereof, whereby 55 said member will engage each partially closed container top with a wiping action and fold and press it into contact with the top of the container body, with a relatively greater pressure on the central portion of the bag top, directly 60 beneath said pivot, than at the sides thereof.

3. In an apparatus for closing and sealing filled bags, means for advancing the bags along a pre-determined path subsequent to having the walls of their open tops partially folded into closing relation, gum applying means, and a mechanism positioned to receive each partially folded bag top from said gum applying means, while supported in an upright position, comprising a member mounted for swinging movement from a pivot 70 disposed over the medial plane of the bag and movable crosswise to the travel of the bags and adapted to engage each partially folded bag top with varying pressure and fold it into sealing engagement with the bag body by a wiping action. 75

4. In an apparatus for closing and sealing filled bags, means for advancing the bags subsequent to having the walls of their open tops partially folded into closing relation, a mechanism positioned to receive each partially folded bag top while supported in an upright position, comprising a member movable crosswise to the travel of the bags and adapted to engage each partially folded bag top and fold it into sealing engagement with the bag body by a wiping action, and means operable by movement of said member to prevent the partially folded bag tops from unfolding, when delivered to said mechanism, and before they are engaged by said member.
5. In an apparatus for closing and sealing filled bags, means for advancing the bags, gum applying means, a mechanism positioned to receive each bag top from said gum applying means comprising a member movable crosswise to the travel of the bags and adapted to engage each bag top and fold it into sealing engagement with the bag body by a wiping action, and means operable by movement of said member and cooperating to complete the closing and sealing of the bag top.
6. In an apparatus of the class described, means for receiving a bag whose open top walls have been partially folded into closing relation, a movable straight edge adapted to engage the partially folded bag top to prevent it from unfolding, a shoe member mounted for swinging movement crosswise of the bag top adapted to engage and fold it over said straight edge and into engagement with the bag body, to thereby close the bag, and means whereby the straight edge is moved out of engagement with the bag top by movement of the shoe member.
7. In an apparatus of the class described, a mechanism adapted to receive a bag whose open top walls have been partially folded into closing relation, said mechanism comprising a guide member and a shoe member between which the partially folded bag top is fed in substantially an upright position, said members being movable crosswise of the bag top, and the guide member operating to prevent the partially folded bag top from unfolding, when received between said members, and the shoe member engaging the bag top and folding it downwardly into sealing engagement with the bag body with a wiping action, and means on the shoe member for engaging the guide member and moving it out of the path of the shoe member.
8. In an apparatus of the class described, means for conveying the bags, an element adapted to engage the bag top, a shoe member mounted for swinging movement from an axis disposed lengthwise of the conveying means, adapted to engage the bag top with a wiping action and fold it smoothly into sealing engagement with the bag body, and means on the shoe member for actuating said element to move it out of engagement with the bag top.
9. In an apparatus of the class described, means for receiving a bag whose open top has been partially folded into closing relation, a straight edge adapted to engage the partially folded bag top to prevent it from unfolding, a shoe member spaced from said straight edge and mounted for movement crosswise of the bag top and adapted to engage the latter with a wiping action and fold it into sealing engagement with the bag body, means for varying the spacing between said straight edge and said shoe member, whereby the apparatus may be adjusted for handling bags of different sizes, and a pivot common to the straight edge and the shoe member.
10. In an apparatus of the class described, means for receiving a bag whose open top has been partially folded into closing relation, a guide member mounted for swinging movement over the partially folded bag top and normally positioned to engage the latter to prevent it from unfolding, a shoe member also mounted for swinging movement over the bag and operatively associated with said guide member, said shoe member being adapted to engage the partially folded bag top and fold it into sealing engagement with the bag body by a wiping action, and means on said shoe member adapted to engage means on said guide member to thereby actuate the latter.
11. In an apparatus of the class described, a conveyer, a station adapted to receive a bag therefrom whose top has been partially closed, and cooperating members at said station spaced apart to receive the partially folded bag top therebetween and adapted to fold it firmly and smoothly into engagement with the bag body, said cooperating members being movable together as a unit.
12. In an apparatus of the class described, a conveyer, a gumming mechanism, a station adapted to receive a bag from said gumming mechanism, cooperating members at said station spaced apart to receive the bag top, means on one of said members engageable with the other of said members to vary the spacing between said members; means for operating said members in timed relation to the movement of the conveyer, and whereby each time a bag is delivered to said station, said members will be operated as a unit to fold the walls of the bag top into sealing engagement with the bag body with a wiping action, and whereby the bag top walls are pressed smoothly into contact with the bag body with the maximum pressure applied to the bag top in the region of its center, and means whereby the various parts of the apparatus may be relatively adjusted to adapt it for handling bags of different sizes.
13. In an apparatus for closing and sealing filled bags, means for advancing the bags, gum applying means, a mechanism positioned to receive each bag top from said gum applying means comprising a member movably mounted over the bags and adapted to engage each bag top and fold it into sealing engagement with the bag body by a wiping action, and means operable by movement of said member, and cooperating therewith to complete the closing and sealing of the bag top.

HELMER ANDERSON.
